Primary Examiner — Wendy L Arminio*Assistant Examiner* — Tracey J Bell(74) *Attorney, Agent, or Firm* — Rothwell, Figg, Ernst & Manbeck, P.C.(57) **CLAIM**

The ornamental design for a clasp, as shown and described.

DESCRIPTION

FIG. 1 is a front right perspective view of a clasp showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front right perspective view of a clasp in open position thereof; and,

FIG. 9 is a front right perspective view of a handbag and clasp thereof.

The handbag shown in broken lines in FIG. 9 depicts environmental subject matter that forms no part of the claimed design.

1 Claim, 6 Drawing Sheets
